DEVICE FOR AND METHOD OF PROTECTING
HOG-CARCASS TONGUES

Reuben J. Gunderson, Chicago, Ill.

Application February 23, 1937, Serial No. 127,059

9 Claims. (Cl. 17—1)

The invention relates to the protection of the tongues of hog carcasses during the machine dehairing operation following the sticking or slaughtering step.

5 In machine dehairing a hog the carcass is subjected to severe beating which frequently displaces the tongue and causes it to be mutilated or punctured by the teeth. Any such mutilation requires removal of the mutilated or punctured portion of the tongue to avoid contamination and reduces the value of the tongue as a food product. It has heretofore been proposed to use a sheath-like protector enveloping the loose portion of the tongue to prevent mutilation during the machine dehairing operation. Such a protector has proved in practice to be unsatisfactory on account of the failure of the protector to remain in its proper place in the mouth of the hog during the beating to which the carcass is subjected in connection 10 with the dehairing operation, and also on account of the labor and difficulty involved in the insertion of the protector in, and its removal from, the mouth of the hog.

The primary object of the invention is to provide 25 a tongue protector device which will not be displaced from the mouth of the hog during the machine dehairing operation and is so designed and constructed that it serves efficiently to protect the tongue against mutilation. In general 30 this device comprises a plurality of resilient arms which serve to hold the tongue within the teeth of the lower jaw of the carcass and are adapted to be interposed between the top of the tongue and the roof and sides of the mouth of the hog, as contra-distinguished from around or in enveloping relation with the tongue. When the tongue is confined in, and pressed into, the lower jaw of the hog and retained by resiliency or spring pressure, it will be effectively held against displacement by the beaters of the dehairing machine. The device as the result of its design and construction permits of ready placement within, and removal from, the mouth of the hog carcass and thus effects a saving of labor.

45 Other objects of the invention are to provide: an improved protector device which comprises resilient arms or members adapted to expand in the jaw, and to confine the tongue in the lower jaw against displacement; and a protector which 50 is efficient in operation and can be manufactured at a low and reasonable cost.

Additional objects of the invention will be apparent from a consideration of the following detailed description.

55 The invention consists in the several novel fea-

tures which are hereinafter set forth and are more particularly defined by claims at the conclusion hereof.

In the drawings which accompany and form a part of this specification or disclosure and in which like numerals of reference denote corresponding parts throughout the several views:

Figure 1 is a side elevation showing a tongue protector device embodying the invention in its operative position in the mouth of a carcass; 10

Figure 2 is a section on the line 2—2 of Figure 1;

Figure 3 is a perspective of the protector device after removal from the mouth of the hog carcass;

Figure 4 is a vertical section illustrating a tool 15 for use in inserting the protector into the mouth of the hog, in readiness to release the protector device so it will spring into its operative position; and

Figure 5 is a horizontal section illustrating the 20 tool after the protector device has been released and has sprung into operative position.

The improved protector device is preferably made of two U-shaped flat spring-metal strips *a* and *b* which form arms or members adapted to 25 expand automatically in the mouth of the hog so they will be secured therein against displacement and press the tongue into and confine it in the lower jaw. The medial portions of the strips are crossed and secured together, as by welding, 30 at their crossing. The arms or members on one strip are adapted to be expanded and contracted in a plane substantially at right angles to the arms of the other strip.

The strip *a* comprises two divergent lower and upper arms or members *8* and *9* which are normally held apart or in expanded relation by the inherent resiliency of the strip. Arm or member *8* is adapted to overlie and press directly against the tongue of the hog carcass and arm or member *9* is provided at its free end with upturned or bent teeth *10* for engaging the soft formation at the back of the roof of the mouth of the hog to prevent displacement of said member. When the protector has been placed in its operative 45 position in the mouth of the carcass, the free ends of arms *8* and *9* will be flexed and pressed together, as illustrated in Fig. 1, sufficiently to cause arm *8* to exert a very firm pressure on the top of the tongue and confine the latter in the 50 lower jaw of the hog, while the upper arm *9* will be caught in the roof of the mouth.

The strip *b* comprises two normally divergent, laterally extending resilient arms or members *11* and *12*, which are provided with out-turned teeth 55

13 at their free ends, to enter and engage the inner sides of the cheeks of the carcass. Normally, the free ends of arms or members 11 and 12 are spread apart sufficiently so that when they 5 are compressed to engage the cheeks they will be under sufficient spring pressure or compression to cause the teeth on their free ends to remain embedded in the cheeks and aid in securing the protector against displacement. The arms or 10 members 11 and 12, when secured in the mouth of the hog, are forwardly convergent at the crossing of the strips *a* and *b* and serve to secure the upper and lower arms or member 8 and 9 against lateral displacement and to aid in holding the 15 protector against displacement.

The protector constitutes a resilient device which is adapted to be placed in the hog's mouth over the top of the tongue and which will be under sufficient pressure, when in the mouth of 20 the carcass, to confine completely and firmly the tongue against displacement in the lower jaw and to secure the protector against displacement from the mouth. The opposed upper and lower arms 8 and 9 will provide the desired pressure 25 to hold the tongue in the lower jaw and the opposed laterally compressed arms or members 10 and 11 coact with the upper arm 9 to secure the protector against displacement from the mouth of the hog during the beating of the hog 30 carcass in the dehauling operation.

In practice, it has been found that a protector device composed of resilient or spring arms whereby the tongue will be pressed into and confined in the lower jaw, and secured against displacement, will effectively protect the tongue because the blows imparted to the carcass while it is being dehaired will not cause the spring-pressed members to lose their grip in the upper jaw and the cheeks.

40 In order to facilitate placement of the resilient protector device in the mouth of the hog carcass a tool like that shown in Figures 4 and 5 is provided. This tool is adapted to press or flex together the resilient arms or members of the 45 protector device while they are being inserted into the mouth of the hog and to release them in such manner that they will spring outwardly into their operative position. As shown in the drawings, the tool comprises a hollow cylindrical body 16 with a handle 17; a barrel 18 slidably 50 fitted around the outside of the body 16; a plunger 19 slidable in the bore of the body 16 and connected to the barrel 18 by a cross-pin 20 which extends through longitudinal slots 21 in body 16; a spring 22 for retracting the barrel 55 18 interposed between the closed outer end 23 of body 16 and plunger 19; and a spring-pressed trigger 24 which is adapted to lock the plunger 19 and the barrel 18 in its extended or operative 60 position, as shown in Fig. 4, at which time the outer end of the barrel 18 projects beyond the closed end 23 of body 16 sufficiently to receive and retain the arms 8, 9, 11 and 12 in compressed or contracted relation for insertion into the mouth of the hog.

65 The method of inserting the protector consists in pulling the barrel 18 outwardly against the force of spring 22 so that the barrel is locked in its extended position by trigger 24, the plunger 70 19 being simultaneously pulled outwardly and compressing the spring 22 which is adapted to retract the barrel; inserting the small end of the resilient protector device into the barrel 18 until it strikes the closed end 23 of body 16 which 75 will flex and spring all of the arms 8, 9, 11 and

12 together and cause them to be automatically retained in the barrel, as illustrated in Fig. 4, with their free ends close together for easy insertion into the rear portion of the mouth of the hog; inserting the protector device and barrel 18 into the mouth of the hog and bringing the free ends of the resilient arms into position to snap, when released, into operative position; and pulling the trigger 19 so that plunger 19 will be released and barrel 18 and the plunger 10 will be shot by spring 22 to withdraw the extended portion of the barrel from the mouth of the hog, as shown in Fig. 5.

As the spring-arms of the protector device are released by the barrel, they will snap outwardly 15 and spread apart. The arm 8 will be firmly pressed against the top of the tongue and arm 9 will be pressed upwardly so its teeth 10 will dig into the soft portion at the top and back of the mouth. Arms 11 and 12 will be spread and 20 pressed laterally so their teeth 13 will dig into the cheeks of the hog and, thereupon, the protector will be automatically and securely held in the mouth of the hog, and will hold the tongue firmly seated within the lower jaw so it cannot 25 escape or pass between the hog's teeth with sufficient pressure effectively to prevent the protector device from being displaced from the mouth while the carcass is passing through the dehauling machine. After the hog has been 30 dehaired, the protector can be easily removed by pressing the members together sufficiently to release the teeth 10 and 13 from the mouth and the cheeks and withdrawing the protector device from the mouth.

35 The invention exemplifies a protector device for the tongue of a hog carcass while it is being dehaired, which effectively prevents the mutilation or puncturing of the tongue and is simple and can be readily inserted and removed. The 40 invention also exemplifies a tool which expedites the placement of the protector in its operative position.

The invention is not to be understood as restricted to the details set forth, since these may 45 be modified within the scope of the appended claims, without departing from the spirit and scope of the invention.

What I claim as new and desire to secure by Letters Patent is:

50 1. A tongue protector comprising a pair of expandable arms adapted to be pressed together and placed in the mouth of a carcass between the tongue and the top of the mouth and operating, when so placed and then released, to spring apart vertically and hold the tongue against the lower jaw, and a pair of laterally expandable arms connected to the first mentioned arms and adapted to be pressed together in connection with placement of said first mentioned arms in the mouth 55 of said carcass and upon release thereof to engage the sides of the mouth and hold the protector in place.

60 2. A tongue protector comprising a pair of rearwardly divergent expandable arms adapted to be pressed together and inserted into the mouth of a carcass and arranged in such manner that upon release thereof one is adapted to overlie and press the tongue downwardly against the lower jaw and the other is adapted to engage the upper jaw, and rearwardly divergent, laterally expandable arms for engaging the sides of the mouth of the carcass and holding the first mentioned arms in place.

65 3. A tongue protector comprising a one-piece, 70

U-shaped spring-strip adapted to be inserted while in a compressed condition into the mouth of a carcass and then released, consisting of a lower spring-arm for pressing the tongue downwardly against the lower jaw and an upper arm adapted to press against and engage the upper jaw, and means connected to the central portion of the spring-strip for holding the strip-formed arms in place.
